UNITED STATES PATENT OFFICE

96,037

DESIGN FOR AN ASH TRAY

Russell P. Harshberger, Pasadena, Calif.

Application April 15, 1935, Serial No. 56,383

Term of patent 7 years

To all whom it may concern:

Be it known that I, Russell P. Harshberger, a citizen of the United States, residing at Pasadena, in the county of Los Angeles and State of California, have invented a new, original, and ornamental Design for an Ash Tray, of which the following is a specification, reference being had to the accompanying drawing, forming part thereof.

Figure 1 is a perspective view of an ash tray embodying the features of the invention.

Fig. 2 is a view of said ash tray in side elevation.

I claim:

The ornamental design for an ash tray substantially as shown.

RUSSELL P. HARSHBERGER.
